UNITED STATES PATENT OFFICE.

VINCENT UNTE, OF DETROIT, MICHIGAN.

DESIGN FOR A TOY WHEELBARROW.

55,578.

Specification for Design. Patented June 29, 1920.

Application filed February 2, 1920. Serial No. 355,774. Term of patent 14 years.

To all whom it may concern:

Be it known that I, VINCENT UNTE, a citizen of the United States, residing at Detroit, in the county of Wayne and State of Michigan, have invented a new, original, and ornamental Design for a Toy Wheelbarrow, of which the following is a specification, reference being had to the accompanying drawing, forming part thereof.

Figure 1 is a plan view and

Fig. 2 a side elevation of the toy wheelbarrow.

In the drawing, the sides, handles and connecting portions for the wheel axle are given the contour of the silhouette outline

of a clothed human figure having its arms carrying the axle connections and its legs and feet positioned to form the barrow handles; the figure carries markings indicating the articles of clothing and which may be distinguished by differences in color (not indicated to prevent confusion).

I claim:

The ornamental design for a toy wheelbarrow as shown and described.

VINCENT UNTE.
